UNITED STATES PATENT OFFICE

LOUIS GOLDSTEIN, OF BROOKLYN, NEW YORK, ASSIGNOR TO KNIGHT SLIPPER MFG. CORP., OF BROOKLYN, NEW YORK, A CORPORATION OF NEW YORK

DESIGN FOR A SLIPPER

Application filed March 17, 1931. Serial No. 39,119. Term of patent 3½ years.

To all whom it may concern:

Be it known that I, LOUIS GOLDSTEIN, a citizen of the United States and a resident of the borough of Brooklyn, county of Kings, city and State of New York, have invented a new, original, and ornamental Design for Slippers, of which the following is a specification, reference being had to the accompanying drawings, forming part hereof.

Figure 1 is a plan view of a slipper showing my new design, and

Figure 2 is a side elevational view of the same.

I claim:

The ornamental design for a slipper as shown.

LOUIS GOLDSTEIN.
